CLAIM

The ornamental design for a grille for automobile and/or other replica thereof, as shown and described.

DESCRIPTION

FIG. 1 is a left, front perspective view of a grille for automobile and/or other replica thereof showing our new design;

FIG. 2 is a left, rear perspective view thereof;

FIG. 3 is a top plan view thereof;

FIG. 4 is a left side elevation view thereof;

FIG. 5 is a right side elevation view thereof; and,

FIG. 6 is a front elevation view thereof.

The portions of the automobile shown in dot-dash broken lines represent an unclaimed boundary distinguishing claimed and unclaimed portions of the claimed design, all other broken lines are shown for environmental and illustrative purposes that form no part of the claimed design.

1 Claim, 6 Drawing Sheets---
